UNITED STATES PATENT OFFICE.

LEVI A. DISBROW, OF OWATONNA, MINNESOTA.

CHURN AND BUTTER-WORKER.

1,114,738.

Specification of Letters Patent.

Patented Oct. 27, 1914.

Application filed June 9, 1913. Serial No. 772,582.

To all whom it may concern:

Be it known that I, Levi A. Disbrow, a citizen of the United States, residing at Owatonna, in the county of Steele and State of Minnesota, have invented certain new and useful Improvements in Churns and Butter-Workers, of which the following is a specification.

My invention relates to combined churns and butter workers and has for its object to provide such a structure which shall be simple and efficient in operation, have relatively few parts and have these parts so arranged as to be particularly accessible for cleaning purposes.

It is also an object of my invention to provide a movable shelf and slicer bars in combination with a central roller having an angular relation such that all of the butter in the churn will at each revolution of the same be carried beneath said roller and upon and over or between said slicer bars.

In my prior Patent No. 953,738 I proposed to use a central roller in combination with a shelf and a series of slicer bars. Each of these slicer bars and the shelf were, however, radially positioned with respect to the roller, the result being that a considerable part of the butter might be carried by the shelf entirely above and over the roller, which proved unsatisfactory in operation and required the use of a multiplicity of slicer bars, three being shown in the said patent although even that number was insufficient for the best work with radially positioned bars and shelf. As the result of extended tests and experiments I have discovered that by placing the shelf so that the surface thereof extends obliquely with respect to the radial line passing through the axis of the roller or in the plane of a chord extended across the drum at a point materially removed from the roller and positioning the slicer bars with the operative portions thereof between this plane and the roller, not only will all of the butter invariably be passed over or between said slicer bars and be much more efficiently worked than if radial elements were employed, but no more than two of such slicer bars will be required. Such an organization is shown in this application. The slicer bars also are turned relative to the roller so that the plane of any surface of said slicer bars is not radial with respect to the axis of the roller, the front edges of the slicer bars

being beveled and having the planes of such beveled portions extending obliquely forward of a plane passing through the axis of the roller and the most forward portion of 60 said slicer bars.

The full objects and advantages of my invention will appear in connection with the detailed description thereof and are particularly pointed out in the claims. 65

In the drawings, illustrating the application of my invention in one form, Figure 1 is a side elevation of a churn employing features of my invention. Fig. 2 is a sectional plan view with some parts broken 70 away. Fig. 3 is a sectional elevation view.

My improved churn comprises an outer cylindrical shell or drum 10 and end members 11 and 12, said end members being supported by trunnions 13 in bearings 14 75 formed at the top of standards 15. The churn is driven by means of gearing 16 from a pulley 17 in a well-known way. The trunnions 13 are hollow, and through the hollow portions thereof extends the 80 shaft 18 of a central roller 19 which may be of any desired form and is shown as having four wings 20. The gearing illustrated drives the drum 10 in one direction and the roller 19 in the opposite direction at a considerably higher rate of revolution than that of the drum. Secured to the ends 11 and 12 of the drum 10 is a shelf 21, which shelf extends endwise across the extent of the drum and laterally in a plane falling 90 in a chord of the circumference of the drum, which plane will cut the radius of the drum from the axis of the roller at approximately its middle point, the shelf being of such width as to leave a space between its inner edge and the drum approximately equal to the width of the shelf. The lower side of the shelf is preferably beveled at each edge, there being a space 22 between the shelf and the drum wall 100 which is essential for producing satisfactory results, as this permits water to drain back as the shelf comes up. 95

Disposed so as to have the operative portions thereof extend above the plane of the shelf 21 is a slicer bar 23 having a beveled edge surface 24 adjacent the shelf 21. Said slicer bar is turned obliquely with respect to a plane passing through the axis of the roller, all surfaces of such slicer bar being 110 oblique to such a plane, as clearly shown in Fig. 3. The slicer bar 23 will be so posi-

tioned that the roll of butter from the shelf 21 will, by gravity, tend to descend against the beveled face of this slicer bar and will come within the action of the wings 20 on the roller 18, which will draw said roll of butter inwardly and squeeze the same upon and over the beveled face 24 and exposed upper edge of the slicer bar 23. It is practicable, and in many cases desirable, to 10 employ another slicer bar 25, which will be spaced a suitable distance from slicer bar 23 and have the operative portions thereof between the roller 19 and the plane of the upper surface of shelf 21. The second slicer bar 25 will have a front beveled face 26 and will be disposed relative to the roller 19 exactly as is slicer bar 23, that is, all surfaces of slicer bar 25 will be in planes oblique to a plane passing through the axis 20 of roller 19.

In view of the fact that slicer bar 25 is relatively at the rear of slicer bar 23, it will have to occupy a position cross sectionally oblique to that of slicer bar 23 in order 25 that the faces thereof may have the same relative position with respect to roller 19. It will be seen that butter which is turned over the edge of slicer bar 23 will be forced upon the surface 26 of slicer bar 25 and squeezed between the slicer bars and over the edge of slicer bar 25 by the wings 20 of roller 19 before descending to the bottom of the drum. In no case, where the 30 slicer bars and shelf are relatively positioned, as herein shown, is there any need 35 for more than two slicer bars to most effectively work the butter after the same is churned.

At suitable distances from shelf 21, I provide 40 a series of short projections 27, preferably backwardly beveled in respect to the direction of rotation of the drum. These bars 27 keep the butter rolling at the bottom so that the buttermilk and water may 45 come next to the interior of the drum and sliding or smearing of the butter will be prevented.

It is to be noted that the arrangement of shelf and slicer bars in respect to the drum 50 19 as shown in this application not only gives an organization of parts in the highest degree effective in the working of the butter, but is also equally efficient in aiding the churning, as the cream is caused to pour 55 from the shelf 21 upon the slicer bar 23 and from there is deflected against the roller 19, from which it is thrown back upon the slicer bar 25 giving exactly the right stirring and breaking action.

60 The advantages of my invention are obvious and have been fully pointed out in the detailed description thereof.

It will be apparent that a combined churn and butter worker made in accordance with 65 the principles of my invention may be man-

ufactured cheaply and will be extremely convenient to use and keep clean.

I claim:

1. A combined churn and butter worker comprising a horizontal rotary drum, a 70 roller centrally positioned within the drum, a shelf positioned adjacent a wall of the drum, the upper surface of said shelf falling in a plane materially removed at its nearest point from the axis of said roller, and a 75 fixed slicer bar extending longitudinally of said drum and across the plane of said shelf and having the edge thereof nearest the axis of the roller operatively positioned between the plane of the shelf and the axis of 80 the roller.

2. A combined churn and butter worker comprising a horizontal rotary drum, a roller centrally positioned within the drum, a shelf positioned adjacent a wall of the 85 drum, the upper surface of said shelf falling in a plane materially removed at its nearest point from the axis of said roller, and a fixed slicer bar extending longitudinally of said drum and across the plane of said shelf 90 and having the edge thereof nearest the axis of the roller operatively positioned between the plane of the shelf and the axis of the roller, said edge being beveled toward the shelf, and said beveled edge and the side 95 of the bar away from the shelf falling in planes on the same side of the axis of the roller as the shelf.

3. A combined churn and butter worker comprising a horizontal rotary drum, a 100 roller centrally positioned within the drum, a shelf positioned adjacent a wall of the drum, the upper surface of said shelf falling in a plane materially removed at its nearest point from the axis of said roller, a plurality 105 of fixed slicer bars extending longitudinally of said drum and having the edges thereof nearest the axis of the roller operatively positioned between the plane of the shelf and the axis of the roller, each of said bars having the edge nearest the roller beveled on the side toward the shelf and the intersecting planes of the beveled and non-beveled surfaces of each of said slicer bars falling outside of the axis of said roller and 110 between said axis and the shelf.

4. A combined churn and butter worker comprising a horizontal rotary drum, a roller centrally positioned within the drum, a shelf positioned adjacent a wall of the 120 drum, the upper surface of said shelf falling in a plane materially removed at its nearest point from the axis of said roller, and a fixed slicer bar extending longitudinally of said drum and across the plane of said shelf 125 and having the edge thereof nearest the axis of the roller operatively positioned between the plane of the shelf and the axis of the roller, said edge being located approximately in a line with and midway between 130

the inner edge of the shelf and the operative periphery of the roller.

5. A combined churn and butter worker comprising a horizontal rotary drum, a roller centrally positioned within the drum, a shelf positioned adjacent a wall of the drum, the upper surface of said shelf falling in a plane materially removed at its nearest point from the axis of said roller, a fixed 10 slicer bar extending longitudinally of said drum and across the plane of said shelf and having the edge thereof nearest the axis of

the roller operatively positioned between the plane of the shelf and the axis of the roller, and a series of butter-turning bars projecting inwardly from the wall of the drum at points separated from the shelf and slicer bars. 15

In testimony whereof I affix my signature in presence of two witnesses.
